ABSTRACT: A soleholder carrier is pivoted to a mounting, e.g., the baseplate, on an axis which is vertical or transverse to the ski. The soleholder carrier is also connected to the mounting by a detent device, which is automatically releasable in response to an overload. The concave detent socket member is adjustably mounted on that part of the appliance which carries said socket member and in such a manner that its angle or area of contact with the convex detent element is variable to vary the force required for a release.

HEEL- OR TOE-HOLDING APPLIANCE FOR SAFETY SKI BINDINGS

The present invention relates to toe- or heel-holding appliances for safety ski bindings, which appliances have a soleholder carrier, which is pivotally connected to a mounting, e.g., the baseplate, on at least one axis which is vertical or transverse to the ski, and which soleholder carrier is also connected to the mounting by a detent device, which is automatically releasable in response to an overload.

In the known two toe- or heel-holding appliances of this kind, the force required for a release is adjustable by a change of the initial stress of the spring which acts on the detent element of the detent device. In these appliances, means must be provided for an adjustable mounting of the abutment for the spring, and the heel-holding appliances require additionally a device which permits of an arbitrary opening of the appliance. Besides, the appliances have a relatively large overall length, owing to the relatively long springs which are required, and the spring forces are so large that the initial stress of the springs can be changed only by means of a tool.

It is an object of the present invention so to design a toe- or heel-holding appliance of the kind described hereinbefore that the same is at least as reliable as the known appliances as regards the safety function but is free of the disadvantages of said known appliances.

Based on a toe- or heel-holding appliance for safety ski bindings, which appliances comprises a soleholder carrier, which is pivoted to a holder, e.g., the baseplate, on an axis which is vertical or transverse to the ski, and which soleholder carrier is also connected to the mounting by a detent device, which is automatically releasable in response to an overload, this object is accomplished according to the invention in that the concave detent socket member is adjustably mounted on that part of the appliance which carries said socket member and in such a manner that the extent of its angle or area in contact with the convex detent element is variable to vary the force required for a release. With this design, a larger angle or area of contact between the detent socket member and the convex detent element will require the soleholder carrier to move a larger distance to the point of release so that the elastic range which precedes the release will be desirably increased with a harder setting.

In a special embodiment of the invention, the convex detent element of the detent device may consist of a roller and the detent socket member may be pivoted to that part of the apparatus which carries said socket member on an axis which in the locked position coincides with the axis of the roller.

In a toe-holding appliance which is releasable toward two directions, it is a feature of the invention that the detent socket member is bipartite and the contact angle or area is variable at both ends in the same sense. In this connection it has proved desirable that the changes of the contact angle or area at both ends are independent of each other.

In a further development of the invention, a heel-holding appliance may be provided with a grip, which is operable against a restoring force and serves to disengage the convex detent element from the detent socket member. In this case, the detent socket member may carry a lever arm, which is urged by a retaining spring against an adjustable stop, or the detent socket member may be provided with a crankpin, which engages a recess in a slide, which is urged by a retaining spring against an adjustable stop.

A plurality of embodiments of the invention will now be described in detail hereinafter with reference to the accompanying drawings, in which:

FIG. 1 is a central longitudinal sectional view showing a toe-holding appliance according to the invention.

FIG. 2 is a top plan view of FIG. 1 but is partly cut open for a better representation of essential parts.

FIG. 3 is a central longitudinal sectional view showing a heel-holding appliance according to the invention in its locked position.

FIG. 4 is a sectional view similar to that of FIG. 3 and shows the heel-holding appliance in its unlocked position.

FIG. 5 is a side elevation showing the heel-holding appliance of FIGS. 3 and 4, and

FIGS. 6 and 7 show a second embodiment of the means for adjusting the force required for a release and for an arbitrary opening of a heel-holding appliance according to FIGS. 3 to 5.

The heel-holding appliance shown in FIGS. 1 and 2 is a so-called double-pivot toe iron. It comprises a baseplate 1, which is adapted to be connected to the ski by screws and in which a vertical pivot pin 2 is fixed by riveting. A pivoted member 3 is freely rotatably mounted on the pivot pin and at its right-hand end in the drawing carries a pivot pin 4, on which a soleholder carrier 5 is rotatably mounted. A soleholder 6 is mounted on the carrier for adjustment in height to different sole thicknesses by means of a screw 7, which extends through a slot 8 in an upwardly angled arm of the carrier. At that end which is remote from the soleholder 6, the carrier 5 carries the detent element 9 of a detent device. The socket member 10 of said detent device is mounted on the pivoted member 3 by means of a screw 11. The detent element consists of a roller and under the action of a helical compression spring 12 and a connector 13 is normally held in its outer limiting position shown on the drawing. The free ends of a vertical part of the connector are received by two diametrically opposite guide grooves 14, which open outwardly into a tapped hole, into which a plug 15 is screwed, which forms the abutment for the helical compression spring 12.

According to the present invention, the detent socket member 10 is bipartite and adjustably held to the pivoted member 3. The socket member 10 consists in the present case of the two circular ring sectors 16, 17 (see FIG. 2), which are provided each with a fixing lug 18 or 19 in the shape of a cockscomb. These lugs are fixed by a screw 11 to the pivoted member 3. To adjust the detent socket member so as to vary its contact angle, each lug is formed with a slot 20, which receives the screw 11 and has a center of curvature that coincides with the axis of the roller 9 when the latter is in its outer limiting position. In the showing in FIG. 2, the detent socket member is shown adjusted to its largest possible contact angle. When the screw 11 is loosened, the retaining lugs 18, 19 can be caused to overlap until the two circular ring sectors abut.

When the soleholder carrier 5 is acted upon by a force which tends to rotate the soleholder carrier relative to the pivoted member 3 and which exceeds the initial stress of the helical compression spring 12, the roller 9 will run up on the corresponding part 16 or 17 of the detent socket member and will increase the stress of the spring 12. If the force acts only for a very short time or is not sufficient for a release, the decrease of the force will cause the soleholder carrier 5 to swing back to its initial position. On the other hand, if the soleholder carrier is acted upon by a force which is sufficient for a release, the spring 12 will be compressed until the roller 9 can pivotally move out of the detent socket member so that the soleholder carrier 5 can continue its pivotal movement virtually without any effort.

As has already been stated in the introductory part of the specification, the force required for a release of the known toe-holding appliances which have a detent-locked soleholder carrier is variable by an adjustment of the initial stress of the spring acting on the detent element. In contrast thereto, the initial stress of the spring is not changed in the appliance according to the invention but the contact angle of the detent socket member is increased to increase the force required for a release, or decreased to decrease said force. This adjustment results in an earlier or later disengagement of the detent element from the detent socket member and consequently in a larger or smaller increase of the stress of the helical compression spring 12 before the release. At the same time, this design results in an advantageous increase of the elastic range which precedes the release in the case of a harder setting.

The two circular ring sectors 16 and 17 which together form the detent socket member can be adjusted independently of each other so that the forces required for a release to one side and the other may be independently adjusted.

FIGS. 3, 4 and 5 show a heel-holding appliance which is designed in accordance with the invention. This apparatus comprises a baseplate 21, which is adapted to be screwed to the ski. The baseplate carries a bearing bracket 22, to which a soleholder carrier 24 is pivoted by a pin 23. This soleholder carrier consists of a housing and at its free end is provided with an angled lug forming a closing pedal 25. A soleholder 26 is mounted on the carrier 24 for adjustment in height to different sole thicknesses by means of a screw 27, which extends through a slot 28. A solid of revolution 31 is mounted in the sidewalls 29, 30 of the carrier 24 and recessed in its intermediate part as is shown in FIGS. 3 and 4 so that the land 32 forms a detent socket member. A detent element cooperating with said detent socket member is constituted by a roller 33, which is freely rotatably mounted on a pivoted member 34, which is mounted by a pin 35 on another small bearing bracket 36 on the baseplate 21. Under the action of a helical compression spring 37, the pivoted member 34 is normally held in a limiting position in which it extends toward the heelholder 26. The helical compression spring 37 bears on the bearing bracket 22.

The solid of revolution 31 is provided with a lever 38 between the two sidewalls 29, 30 of the soleholder carrier 24. Under the action of a limb spring 39, this lever is held in engagement with a stop 40. The stop is screw-connected by a screw 41 to the upper wall of the housing; that wall is formed with an elongated hole 42. When the screw has been released, the stop can be displaced and the position of the solid of revolution 31 and of the detent socket member 32 in the housing can be changed. The arrangement of the detent socket member is such that its axis coincides with the axis of the roller 33 when the appliance is in locking position. The stop 40 has a lateral guide pin 43 (see FIG. 5), which is slideable in a slot 44 in the sidewall 30 of the housing and serves at the same time as a pointer for indicating the adjusted force required for a release. The pointer cooperates with a scale which is provided on one longitudinal side of the slot.

The lever 38 serves as a grip for an arbitrary opening of the appliance. To this end, its free end is angled to the rear and is provided with a depression 45 for receiving the tip of a ski pole. A pivotal movement of the lever in the clockwise sense in the drawings and opposite to the force of the limb spring 39 enables a rotation of the detent socket 32 to such an extent that the roller 33 can no longer be urged back when the soleholder carrier 24 is pivotally moved upwardly.

As a heel-holding appliance is released only in one direction, namely, upwardly, different from a toe-holding appliance, it will be sufficient if the detent socket member is adjustably mounted with respect to its lower end in the drawings. The detent socket member need not be bipartite as in a toe-holding appliance. FIG. 3 shows the heel-holding appliance in the locking position. If the soleholder 26 is acted upon by an approximately upwardly directed tensile force, said force will tend to rotate the carrier 24 about the axis 23. The force applied will succeed in doing so when it is larger than the force that is due to the initial stress of the helical compression spring 37. In this case, the roller 33 will run up on the detent socket member 32 and will increase the stress of the spring. If the force acts only for a very short time and does not reach the value required for a release, a decrease of the force will cause a return pivotal movement of the soleholder carrier 24 into the position shown in FIG. 3. If the force acting on the soleholder is sufficient for a release, the pivoted member 34 will compress the spring 37 to such an extent that the roller 33 enables a passing of the detent socket member 32. When the detent socket is released, the soleholder carrier 24 can continue its movement as far as to the unlocking position, shown in FIG. 4, virtually without an effort.

The drawing shows the heel-holding appliance as adjusted to the highest force required for a release. A shifting of the stop 40 to the right in the drawing will decrease the contact angle of the detent socket, which angle is significant for the release. As a result, the roller 33 will disengage the detent

socket member 32 before or said detent socket member will disengage the roller 33 before and the helical compression spring 37 will be less highly stressed.

If the heel-holding appliance is intended to cooperate with a toe-holding appliance which requires an engagement by the skiing boot under a contact pressure, the heel-holding device will be supplemented by a suitable device, which is known per se and will not be explained more fully. In this case the baseplate 21 is not screw-connected to the ski but consists of a carriage, which is under the action of a spring and against the force of said spring is slidably to the right in the drawing, toward the rear end of the ski.

FIGS. 6 and 7 show a second embodiment of a means for adjusting the force required for a release and for an arbitrary opening of the heel in two different positions. Instead of the soleholder carrier 24 of the previously described embodiment, a soleholder carrier 46 is provided. A solid of revolution 48 formed with a detent socket member 47 is mounted in the sidewalls of the soleholder carrier. The sidewalls consist in the present case of hollow walls and the solid of revolution is mounted in the inner part of said walls. The same has two coaxial pins 49, which extend into the cavities of the sidewalls and enter transverse slots 50 at the free ends of the limbs of a U-shaped slide 51. The top of the housing is drawn in to some extent adjacent to the slide and forms a bracket 52. A helical compression spring 53 bears on the bracket 52 and acts from the inside on the crosspiece of the slide and urges a lateral extension 54 of the slide against a stop 55. The spring serves only as a restoring means and for this reason is relatively weak. The stop 55 consists of a nut, which is nonrotatably mounted in the housing and adjustable in height in the housing by an adjusting screw 56. The nut may have a guide pin, which is in register with the stop 40 and moves in a vertical slot formed in the sidewall of the housing. The guide pin serves to indicate the force which is required for a release. The slide 51 forms also the handle for an arbitrary opening of the heel-holding appliance and is formed for this purpose in its crosspiece with a depression 57 for the insertion of the tip of a ski pole.

FIG. 6 shows the appliance as adjusted to the highest release hardness. The adjusting screw 56 can be operated to displace the slide 51 downwardly so that the pin 49 acting as a crankpin is driven to rotate the solid 48, as is apparent from FIG. 7. This will reduce the angle of contact of the detent socket 47 on the release side thereof. In other respects, the same remarks are applicable as have been made with reference to FIGS. 3 to 5.

By the application of pressure on the slide 51 against the force of the spring 53, the detent socket member can be pivotally moved to such an extent that a lifting of the soleholder carrier 46 can be lifted virtually without effort because the lock has been released.

I claim:

- 55 1. In a toe- or heel-holding device for safety ski bindings having a base member, a holding-down member pivotably mounted on said base member and detent means disengagably interconnecting said members which is automatically releasable in response to a predetermined overload, the improvement comprising said detent means including a detent element and a detent socket therefor, and means adjustably supporting said detent socket to allow displacement thereof in a plane lying at right angles to the pivot axis of said holding-down member in a direction circumferentially of said detent element without changing the position of said detent element.
- 60 2. In a toe- or heel-holding device according to claim 1, wherein the detent element is formed by a roller, and the detent socket is pivoted to a member of the device carried on an axis coincidental with the axis of the roller.
- 65 3. In a heel-holding device according to claim 2 wherein the detent socket carries a lever arm which under the force of a retaining spring bears on an adjustable stop.
- 70 4. In a heel-holding device according to claim 3, characterized in that the free end of the lever arm serves as a handle for an arbitrary opening of the device.

5. In a heel-holding device according to claim 2 characterized in that the detent socket is provided with a crankpin, which enters a recess of a slide, which under the force of a retaining spring bears on an adjustable stop.

6. In a heel-holding device according to claim 5 characterized in that slide is designed as a grip for an arbitrary opening of the device.

7. In a toe-holding device according to claim 1 the further improvement of the detent socket being bipartite and its con-

tact area being variable at both ends in the same sense.

8. In a toe-holding device according to claim 7, the further improvement of the changes in the contact area at both ends being independent of each other.

9. In a heel-holding device according to claim 1 the further improvement of a grip being provided, which is operable against a restoring force and serves to disengage the detent element from the detent socket.
